OTHER PUBLICATIONS

Lifefitness, "Studio Dumbbell", Mar. 17, 2019. <https://shop.lifefitness.com/studio-dumbbells>. Shown on p. 1. (Year: 2019).*Primary Examiner — Cynthia Ramirez*Assistant Examiner* — Michael A Maharajh(74) *Attorney, Agent, or Firm* — Andrus Intellectual Property Law, LLP(57) **CLAIM**

The ornamental design for an exercise dumbbell, as shown and described.

DESCRIPTION

FIG. 1 is a front perspective view of an exercise dumbbell, showing my new design.

FIG. 2 is a left side view thereof.

FIG. 3 is a right side view thereof.

FIG. 4 is a front view thereof.

FIG. 5 is a rear view thereof.

FIG. 6 is a top view thereof; and,

FIG. 7 is a bottom view thereof.

The broken lines represent portions of the exercise dumbbell that are shown for illustrative purposes only and form no part of the claimed design.
